David G. Lammi, Chicago, Ill.

Application January 29, 1948, Serial No. 144,137

Term of patent 14 years

(Cl. D55—1)

To all whom it may concern:

Be it known that I, David G. Lammi, a citizen of the United States of America, residing in the city of Chicago and State of Illinois, have invented a certain new, original, and ornamental Design for a Single Spindle Hydraulic Paper Drill or Similar Article, of which the following is a specification, reference being had to the accompanying drawings, forming a part thereof.

Fig. 1 is a front elevational view of a single spindle hydraulic paper drill, showing my new design.

Fig. 2 is a side elevational view of said drill.
Fig. 3 is a rear elevational view of said drill.
Fig. 4 is a top plan view of said drill.

I claim:

The ornamental design for a single spindle hydraulic paper drill or similar article, as shown.

DAVID G. LAMMI.
